LAMP SHADE MACHINE

Benjamin Goldberg, New York, N. Y.

Application December 8, 1932, Serial No. 646,348

8 Claims. (Cl. 93—1)

The present invention relates to a machine for forming lamp shades for use in connection, preferably with electric lights or bulbs; with oil lamps, and in connection with other sources of light for 5 fanciful illumination or for reflecting colored light rays, and by diffusion or by reflection either for reading purposes or for decorative effects.

An object of the invention is to provide a machine for forming lamp shades of the types above 10 set forth, by semi-automatically assembling pre-formed stock elements of appropriate character for collectively producing complete lamp shades economically, at a comparatively high productive rate and in two major operations.

15 Another object of the invention resides in providing adjustable means for accommodating lampshades of various sizes or dimensions and means adjustably mounted for folding an adhesive binder, or tape and for guiding the same to operative position in proper assembly with component parts of a lamp shade for binding said parts into coactive relation.

Another object being to provide means whereby materials of any reasonable thickness may be worked, with no adjustment of the machine parts.

Inventive features of the machine construction, are to be found in co-acting male and female rolling devices having respectively fixed and movable mountings and manually operated means for quickly separating the said rolling devices at any time in the operation of said machine, for inserting or withdrawing the stock elements or portions of a lampshade to be united by suitable means hereinafter set forth.

A further inventive feature of the invention resides in interchangeable male and female rotary parts for respectively finishing the top and bottom edges of a lamp shade at high speed.

In the drawings forming part of this specification:

Fig. 1 is a front elevation of the improved lampshade forming machine, omitting the power unit and the tape supply means, and indicating by dot and dash lines, a lamp shade in operative position.

Fig. 2 is a horizontal sectional plan view taken about on the line 2—2 of Fig. 1.

Fig. 3 is a longitudinal vertical sectional elevation of the machine, taken about on the line 3—3 of Fig. 1.

Fig. 4 is an enlarged detail elevation showing co-acting rotary devices for assembling the complementary parts of a lamp shade to form the bottom edge thereof.

Fig. 5 is an enlarged detail elevation similar

to Fig. 4 but showing the means for assembling the complementary parts of the lampshade to form the top or upper edge thereof.

Fig. 6 is a fragmentary composite view showing an adhesive tape support and wetting means and a device or tube for folding and guiding the wet adhesive tape when drawn to the front of the machine to be applied to the edges of a lamp shade.

Fig. 7 is a composite perspective showing the pre-formed parts of a lampshade to be assembled by the machine of this invention.

Fig. 8 is a general side elevation of the completed lamp shade as applied to an electric lamp or bulb.

Fig. 9 is a fragmentary diagrammatic view showing parts of a lamp shade and showing the upper roller die just as it drops into contact with the said parts to begin the binding operation.

Fig. 10 is a detail perspective of the binder tape folding and guiding elements.

Fig. 11 is a section on the line 11—11 of Fig. 10.

Fig. 12 is a detail perspective showing how the wet adhesive side of the binder tape is reversed by a break-fold at the delivery zone close up to roller dies just prior to the binding operation.

Figs. 13 and 14 are side and front views respectively of a guide and break-folding tube for receiving a binder tape.

Referring now to the drawings in detail, a support or table 10 is provided, having a desirable under-frame 11, here shown as of angle-iron and comprising leg pieces 12, and horizontal connecting pieces or rails 13 all riveted together to form a substantial structure. Conveniently located on the table 10, and fastened thereto, is a machine head, generally designated at M. This structure

preferably comprises a pair of parallel upright front and rear plates 14 and 15 respectively, and in each is formed a centrally arranged longitudinal slot 16, extending from about midway their height, upward and through the upper ends thereof. Slidable in the slots 16, are bearing blocks 17 in which a countershaft 18 rotates.

Keyed to the shaft 18, between the plates 14 and 15 is a gear 19, and a presser roller 20 is keyed to the forward end of this shaft to co-act with a shaping roller 21, on a shaft 22 which is driven through a worm gear 23 and worm 24 by a motor 25 controlled by a convenient switch 26.

In carrying out the invention, preferably two pairs or sets of rollers 20—21 are employed, to produce a nicely finished product.

In Fig. 4 of the drawings, the working face of

the presser roller 20 is plane and parallel with the axis of the shaft 18, while the companion or forming roller 21 has a circumferential groove 27 and a back-flange 28. The rollers 20 and 21 are employed to assemble the component parts of the bottom edge of a lamp shade S, by applying an adhesive tape or strap 29, folded longitudinally, partially around a wire ring frame 30, then pressing the wings of the folded tape into intimate contact with the opposite faces of the bottom edge portion of the shade body 31, preferably of heavy decorated or plain paper or other sheet material.

The top edge of the lampshade S is finished or assembled in much the same manner, as best shown in Fig. 5, the only difference being in the cross-section shape of the pressing and forming faces of the rollers 20a and 21a, in which the roller 20a has a working face 20b converging forwardly, while the companion or forming roller 21a has a face 21b diverging forwardly, the angles of convergence and divergence being coincident with each other and with the angularity of the wall of the lamp shade with respect to its own axis, this being clearly shown in the said Fig. 5 of the drawings.

Preferably the finishing adhesive tape, ribbon or strap 29, is normally carried as a supply-roll 35 (Fig. 6) on a suitable bracket 36, on which direction rollers 37 and 38 are journalled and within a water pot 39 is mounted a roller 40, dipping into a body of water 41, which is applied to the under or adhesive side of the tape 29 by frictional contact with roller 40 when said tape is drawn from the supply roll 35 to the front of the machine, through a folding tube 42 by which said tape is folded centrally and longitudinally, after which the tape is drawn through an adjustably supported guide 43 (Figs. 1, 2, 3 and 10 to 13) having a tapered end 43a; the guide 43, is secured to a block 43b formed with a forked portion 43c and a shank 43d, which is passed through a vertical post 43e and secured in adjusted relation by a set screw 43f. The post 43e, is adjustably fixed in a block 43g by a set screw 43h; the block 43g, is adjustably fixed to a second block 43i, by set screws 43j through a cross-bar 43k, said blocks having bores 43l through which they may be secured to the sides of the machine or frame M by suitable screws or bolts 43m, see Fig. 3.

A preferred construction for supporting and adjustably mounting the folding tube 42, which receives folds and guides the binding tape 29 delivered from the supply roll 35 is shown more clearly in Figs. 10 and 11 of the drawings. The tube is preferably of U shaped tubular cross section, and is secured to and supported primarily by an L bracket plate 75 having a longitudinal slot 76; through which a set screw 77, is passed and through a horizontal bracket plate 78, which in turn is connected by screw and slot connections 79, with a side plate 80 of the machine or frame M. Many of the above described details are purposely omitted in the other figures of the drawings to avoid confusion.

The binding tape 29 is folded as at 81 by the folding tube 42, said shape being retained by the member 43 while it reaches the tapered portion 43a where it is break-folded as at 29a by the operator, thus in-folding the outer wet adhesive side 100 to the inner position 101 (see Fig. 12) subsequently to be applied to the opposite sides of the frame-ring 30, and the edge portion of the card-board body 31 of the lamp shade just prior to the application of rolling pressure by the roller-

dies 20—21 to bind the parts and mold the bead edge of the lamp-shade structure.

In the break-fold reverse of the wet sides of the binder-tape, the forked portion 43c of the block 43b, serves to continuously form and guide the reversed portion of the binder-tape in proper position for application to the assembled edge parts of the lamp shade, the final result being shown in Figs. 4 and 5 of the drawings. The end of the tape of course will be properly placed between the rollers 20—21 and over the wire ring frame 30, before starting an assembling operation.

In other words, the operator will initially draw the tape 29 through the U shaped tubular guide 42, and then through the similarly shaped second guide 43, break-folding it at the inclined termination 43a thereof, then guiding it in break-folded condition along and in the U shaped trough-like open channel 43c of guide 43, right angularly continuing the same. Thereupon the tape is applied to initial portions of the lamp shade parts, that is to the wire frame and the sheet material blank between the rollers 20 and 21; the rollers are then started and the parts and the tape will be automatically drawn or threaded through between the rollers until the joint of the shade is finished. New shade parts are then taken and the tape end, cut on finishing the previous shade, applied to them without new preparation of the tape.

Instead of using water on the pre-applied adhesive of the tape 29, a liquid adhesive may be placed in the pot 39 and applied to a dry, non-adhesive tape if desired.

The power shaft 22, has fixed thereto, a gear 44 adapted for operative coaction with the gear 19 on the countershaft 18.

The tops of the frame plates 14 and 15 carry cross-bars 45, which span the slots 16 and are bolted in place; these cross-bars tapped centrally to receive adjusting screws 46, carrying swiveled follower blocks 47, resting on compressed springs 48, through which, yielding contact is established between the rollers 20 and 21.

Tripping means for separating the rollers 20—21 to respectively withdraw or insert finished or unfinished lamp shades, may comprise a foot treadle 49 having a link connection 50, with a rock-bar 51, fixed to a rock-shaft 52, passing through fixed journal blocks 53.

Fixed on the opposite ends of the rock shaft 52, are rock-arms 54, provided with curved recesses 55, through which the counter shaft 18 passes, so that when it is desired to separate the rollers 20—21 when employed, or the rollers 20a—21a, the treadle is depressed, thus drawing rock bar 51 downwardly and raising the respective upper roller.

Adjustably fixed on the table face is a gage frame 56 to support the shade having backwardly directed arms or extensions 57, which pass through keepers 58 and are held by set screws 59.

For attaching the lamp shade to an electric lamp or bulb, one of the ring frames 30, may have connected therewith a spider if desirable, or a cross frame as at 60, formed with clasping loops 61 or the like, for engagement with an electric bulb or other lamp.

The rollers 20—21 and 20a—21a may be termed roller dies, for they form a smooth uniform bead finish on the lamp shade edges.

The rock-bar 51, rock-shaft 52 and rock-arms 54 collectively, constitute a tripper frame 65 for 150

lifting the upper shaft 18, for separating the gears 19 and 44 and the roller dies 20—21 or the roller dies 20a and 21a when in use.

It is understood that modifications may be made in the parts and combinations of my device, and I hereby reserve my right to any and all such changes and modifications as are within the spirit of the invention and the scope of the appended claims.

13 In the operation of my machine, the same is normally at rest and when it is desired to complete a lamp-shade, as described hereinbefore, first pedal 49 is stepped upon so as to separate the rollers in my machine and insert therebetween the tape, the wire ring and the paper blank 31 for the lamp-shade, as best indicated in Fig. 9, whereupon the pedal 49 is released and the said elements of the lamp-shade are caught between the two rollers. Switch 26 is now closed 20 and the machine begins to operate and the lamp-shade finished as described hereinbefore, whereupon the circuit is broken and the machine will stop, after which the pedal 49 is again stepped upon to separate the operating rollers of my 25 machine, take the finished product from therebetween and put a new set of three elements of tape, ring and paper blank between them when a new operation may begin.

What I claim as new, is:

30 1. In a machine of the class described, a break-folding guide, comprising a U shaped tube; means to cause said tape to pass through the opening of said U shaped tube with its adhesive side outwardly and its non-adhesive side riding 35 on the inner wall of said U shaped tube; an inclined termination of said tube; an open U shaped trough-like continuation for said tube to be placed angularly thereto, said trough-like extension being adapted to break-fold said tape at 40 said inclined termination and to cause the same to fold into a U shaped channel formation, its adhesive side being turned inwardly.

2. A machine of the class described, comprising a support; a frame thereon; a power shaft 45 journalled in said frame; a countershaft above said power shaft in parallelism therewith; means to journal said countershaft in said frame in a slidable manner; a gear on each of said shafts; a roller die on each of said shafts; means to yieldingly press said countershaft towards said power shaft and put said gears and roller dies into normally operative contact; a tripper frame rockable in said frame having a portion adapted to 50 rotatably support said countershaft, and means 55 to upwardly move said portion of said tripper frame against said yielding pressure on the countershaft whereby said gears and said roller dies will be disengaged.

3. In a machine as described in claim 2, a pedal 60 on said frame; a link connecting said pedal and said tripper frame whereby a downward pressure on said pedal will rock said tripper frame and cause said support to move upwardly and to disengage said shafts and their associated parts.

65 4. In a machine as set forth in claim 2, said tripper frame comprising a shaft rockable in said frame; an arm by which the same may be rocked, and two oppositely extending arms carrying said countershaft supporting portions.

70 5. In a machine for assembling wire frames and a sheet material body of a lamp shade, or the like, by the use of an adhesive securing tape; two rolling dies; means to cause said dies to tightly engage one another through yielding pressure;

one of said rollers having a groove therein to receive said wire frame and to permit the same to be threaded through between said rollers in said groove; co-operating surfaces on the rollers adjacent to said groove adapted to receive a portion of the sheet body of the lamp shade and of said tape; means to rotate said rollers in co-operative relation so that the two elements of the lamp shade and said securing tape will continuously pass between them under pressure, said tape encircling said frame and engaging said portion of the sheet body, and means to fold said tape and to place the same between the rollers so as to encircle said frame and engage both sides of said sheet body.

6. In a machine for assembling wire frames and a sheet material body of a lamp shade, or the like, by the use of an adhesive securing tape; two rolling dies; means to cause said dies to tightly engage one another through yielding pressure; one of said rollers having a groove therein to receive said wire frame and to permit the same to be threaded through between said rollers in said groove; co-operating straight, cylindrical surfaces on the rollers adjacent to said groove adapted to 100 receive a portion of the sheet body of the lamp shade and of said tape; means to rotate said rollers in co-operative relation so that the two elements of the lamp shade and said securing tape will continuously pass between them under pressure, said tape encircling said frame and engaging said portion of the sheet body, said straight, cylindrical portions of the rollers being substantially parallel with the axes of said shafts.

7. In a machine for assembling wire frames and a sheet material body of a lamp shade, or the like, by the use of an adhesive securing tape; two rolling dies; means to cause said dies to tightly engage one another through yielding pressure; one of said rollers having a groove therein to 110 receive said wire frame and to permit the same to be threaded through between said rollers in said groove; co-operating surfaces on the rollers adjacent to said groove adapted to receive a portion of the sheet body of the lamp shade and of 120 said tape; means to rotate said rollers in co-operative relation so that the two elements of the lamp shade and said securing tape will continuously pass between them under pressure, said tape encircling said frame and engaging said portion of the sheet body, and a folding guide for the tape adapted to fold it into a U shaped channel with its adhesive side inwardly so as to guide the same around said wire frame and the adjacent portion of the sheet body.

8. A machine of the class described, comprising a support; a frame thereon; a power shaft journalled in said frame; a countershaft above said power shaft in parallelism therewith; bearing means for said countershaft slidable in said frame; a gear on each of said shafts; a roller die on each of said shafts; spring means acting between a part of said frame and said slidable bearings to yieldingly press said countershaft towards said power shaft and put said gears and roller dies 135 into normally operative contact; a tripper frame rockable in said frame having a portion adapted to rotatably support said countershaft, and means to upwardly move said portion of said tripper frame against said yielding pressure on the countershaft whereby said gears and said roller dies will be disengaged.

BENJAMIN GOLDBERG.
